CARBURETING APPARATUS

Harry H. Waters, Clinton, Iowa, and Rudolph F. Gagg, Fairlawn, N. J., assignors, by mesne assignments, to Reconstruction Finance Corporation, Chicago, Ill., a corporation of United States

Application November 25, 1932, Serial No. 644,242

17 Claims. (Cl. 123—25)

This invention relates to an improved method and apparatus for carbureting the air for an internal combustion engine.

During the past few years, automotive engineers have realized that the temperature of the fuel in the cylinder chambers has a marked effect upon the efficiency of the engine. Thus, when the engine is running slowly or under light load, the fuel stream should be at a high temperature, and conversely, when the engine is under a heavy load or at high speed, the fuel stream should be comparatively cold. Roughly, the temperature of the fuel stream should vary inversely with the load or speed of the engine. To vary inversely the temperature of the fuel stream with the load or speed of the engine, various devices have come into existence. Uniformly they accomplish their purpose by mixing air preheated by the exhaust pipe with air at atmospheric temperature to obtain a given temperature in the fuel stream. It was also discovered that cold air should not be introduced into the fuel stream immediately upon the application of load to the engine, but should slightly lag the application of load. This was attained in various ways, one of which is disclosed in applicants' application No. 422,644, filed January 22, 1930, now Patent No. 1,901,618, wherein a ball bearing check valve is used.

One reason for delaying the introduction of cold air with an increase of load or upon throttle opening is to prevent upsetting the mixture due to the sudden in-rush of cold air which would result if no delay were provided. Under the effects of a sudden rush of cold air the fuel would not vaporize readily and the mixture would be temporarily disturbed, in some cases sufficiently to cause a temporary faltering of the engine.

In most engines the hot air system is designed for the passage of less air than is required by the engine under full load and the path travelled by the hot air is longer than that travelled by the cold air due to the hot air heating arrangements. If on throttle opening a sudden rush of cold air is permitted to enter the engine through its short path of travel the mixture would be disturbed and faltering may result. On the other hand, by delaying the opening of the cold air conduits the air on acceleration is required to travel momentarily through the longer hot air passage-ways and through the more restricted path. A slightly over-rich mixture is therefore taken into the engine temporarily, which is desirable in assisting the engine to assume the load quickly without any tendency towards faltering. In this respect the delayed admission of the cold air func-

tions similarly to the acceleration pump which is a part of many modern internal combustion engine carburetion systems, particularly as applied to automobiles.

While it is desirable, therefore, to introduce cold air to the engine at full load to increase power and decrease detonation, there is no necessity for the immediate introduction of cold air upon acceleration but, on the contrary, the acceleration characteristics of the engine are considerably improved by a momentary delay of cold air introduction for the reasons stated. The delay arrangement has particular utility in engine installations in which the load upon the engine varies rapidly over a wide range.

Concurrent with this development of temperature control has been experimentation with anti-detonators. To promote the complete and rapid explosion of fuel within the cylinder chamber, a small amount of some fluid such as water or alcohol in the fuel stream is desirable and the amount varies with the load or speed of the engine. Inasmuch as it is desirable to increase the amount of anti-detonating fluid and cold air in the fuel stream directly with the increase in load or speed of the engine, a single device has been utilized to control both. Such a device is shown in the above-mentioned patent of applicants.

However, controlling both the anti-detonating fluid and the temperature of the fuel stream by a single control unit may, in certain installations, be undesirable, due to the slow acting valve which delays the introduction of cold air to the fuel stream. While it is advantageous to delay the injection of cold air to the fuel stream, the contrary is frequently true as to the anti-detonation fluid. It has been established that in certain engines the anti-detonation fluid should be injected into the manifold close to the cylinder chambers as nearly simultaneous with the imposition of load or speed as possible to resist any tendency toward detonation on acceleration. This, a single control device will not accomplish.

It is the object of this invention, therefore, to provide in combination a means for controlling the introduction of cold air into the fuel stream of an internal combustion engine, slightly lagging the imposition of load or speed upon the engine, and a means for injecting anti-detonation fluid into the fuel stream, varying the injection directly and quickly with the imposition of load or speed on the engine.

A second object is to provide jets for the anti-detonation fluid within the manifold in close proximity to the cylinder chambers.

Other objects and features of the invention will become apparent from a reading of the following specification in the light of the accompanying drawing, in which:

5 Figure 1 is a view in side elevation of an internal combustion engine equipped in accordance with the present invention;

Figure 2 is an enlarged horizontal cross section of a portion of the apparatus disclosed in 10 Figure 1;

Figure 3 is an elevational view, in section, taken along the line 3—3 of Figure 2;

15 Figure 4 is a view in side elevation, in section, of the device taken on the line 4—4 of Figure 2; and

Figure 5 is an enlarged elevational view, in section, of a portion of the mechanism included in Figure 1.

As illustrated in the drawing, reference numeral 10 indicates an internal combustion engine provided with an intake manifold 12, a fuel intake 14 leading thereto, a throttle valve 16 for controlling the flow of fuel through the fuel intake, and a carburetor 18. In conformity with 20 the general practice in the art of carbureting air, the engine of Figure 1 is equipped with means for admitting air to be mixed with the fuel as the latter passes to the intake manifold and, in accordance with the principles of the present invention, the temperature of such air depends upon the load or speed of the engine. Thus, hot air may be supplied through a filter or cleaner 20 from whence it flows through a stove 22 surrounding an exhaust pipe 23 before being conducted through a passageway 24 to a temperature control unit 26. Cold air, on the other hand, is admitted through a filter or cleaner 27, which depends from the control unit 26.

As fully disclosed in applicants' Patent No. 40 1,901,618, the control unit 26 comprises a double 45 acting valve 28 actuated by means of a flexible diaphragm 32, the expansion or contraction of which is regulated by variations in pressure occurring within the intake manifold above the throttle valve, such variations being communicated to the interior of the diaphragm through a passageway 34. Inasmuch as the double acting valve 28 is carried by the flexible diaphragm 32, it will be appreciated that fluctuations in pressure 50 imparted to the latter cause the valve to move either toward or away from the diaphragm proper. The valve is double acting for the purpose of controlling the admission of both hot and cold air. When moved upwardly from the dotted line position shown in Figure 1, it gradually 55 closes off the supply of hot air coming down through the passageway 24 and, conversely, when moved downwardly it tends to shut off the supply of cold air.

60 In order to explain the operation of the temperature control unit, let us suppose that it suddenly becomes desirable to open the throttle valve 16, owing to the imposition of a heavier load on the engine or the desire to increase its speed. As 65 soon as the valve 16 is open, any vacuum built up in the intake manifold 12 is destroyed, permitting expansion of the flexible diaphragm 32 by means of a spring located interiorly of the diaphragm. This sudden expansion of the diaphragm moves the valve 28 in the direction of the hot air opening and away from the cold air opening, thereby permitting the influx of cold air when the load or speed of the engine is high. In the reverse operation, let us suppose it suddenly 75 becomes desirable to close the throttle valve to

decrease the speed or to accommodate a lighter load. As soon as the valve is closed, a suction is built up in the intake manifold 12 which, through the passageway 34, is communicated to the interior diaphragm causing a collapsing action of the latter. As the diaphragm collapses, the double acting valve moves in a direction to shut off the supply of cold air and increase the supply of warm air, thereby assuring that heated air will be delivered to the engine at low speeds 10 or loads. To avoid sudden or extreme changes in the temperature of the air flowing into the intake manifold from the control unit 26, a ball control valve 30 is located at the point of junction between the passageway 34 and the flexible 15 diaphragm 32. As shown in Figure 5, the device comprises a small ball valve 36 adapted to control a valve opening 38 which is retained in place by means of a punctured retaining ring 40. Located to one side of the passageway 38 and extending parallel therewith, is a by-pass 42 which permits fluctuations in pressure to be transmitted through the valve even when the ball 36 is on its seat closing the opening 38. In operation, if the throttle valve 16 is suddenly thrown from closed 25 to open position, vacuum within the line 34 is immediately destroyed, causing the ball 36 to fall downward and close the opening 38. However, owing to the small size of the by-pass 42 through which the pressure must now be transmitted to 30 the interior of the diaphragm, the destruction of the vacuum within the diaphragm is delayed or retarded, causing a gradual change in the temperature of the air admitted. This lagging action has been found desirable in order to obtain 35 efficient operation by causing the control valve 28 to lag the imposition of load or speed upon the engine. If the throttle valve is suddenly closed, causing a vacuum to be established in the passageway 34, the ball valve 36 quickly rises to 40 the approximate position shown in Figure 5, opening the passageway 38 and permitting the rapid collapse or constriction of the flexible diaphragm 34 and therefore we see that the operation of the valve 28 does not lag with the decrease of load or speed of the engine. 45

Turning now to the device which controls the injection of anti-detonating fluid, the reference numeral 44 in Figure 1 designates a control unit mounted independently of the temperature control unit 26. The fluid control device is provided with an intake passageway 46 through which flows the anti-detonating fluid that is circulated by means of a suitable pump 48. 50

As shown in Figure 3, anti-detonating fluid 55 flowing through the extremity 60 of the intake passageway 46 moves upwardly through a small passageway 62 bored centrally of a removable plug 58. The amount of fluid flowing through the passageway 62 is controlled by means of a valve 56, the operation of which will be fully set forth hereinafter. From the passageway 62, the fluid enters a larger compartment 54 where it is divided into any number of streams desired (two such streams are shown herein) by means of 60 branch ducts 72, 72 leading to outlets 74, 74. The fluid passing through the outlet passageways enters a plurality of conduits 49, 49, which lead to points immediately adjacent the junction between the fuel intake 12 and the cylinders of the engine. 70

In the fluid control device 44, just as in the temperature control unit 26, the amount of fluid admitted is varied and controlled in accordance with fluctuations in pressure occurring within 75

the intake manifold above the throttle valve. Such fluctuations are imparted to the device through a tube 88 having a screw threaded connection 90 with a bored chamber 92 formed with 5 in the body of the device. A communicating duct 94 leads from the chamber 92 to the interior of a bellows diaphragm 80 which, by means of a cover 76, carries the valve stem 56 hereinbefore referred to. By means of an adjustable lock nut 10 78, the position of the tapered valve 66 with reference to the valve opening 62 may be controlled as desired. As illustrated, the diaphragm is secured at 79 to the body of the control device and at its upper extremity is crimped at 77 to inclose 15 the rim of the cover 76. Located interiorly of the diaphragm for the purpose of normally holding the latter in expanded condition is a compression spring 82 and the extent of the expansion of which the diaphragm is capable is governed by 20 an adjustable guard or stop 84 mounted on projection pins 86.

As shown in the drawing, the valve stem 56 is packed by means of a suitable packing material 68 inclosed by means of a washer 69, which is held in position by the aid of a compression spring 64.

Here also, in operation, variations in pressure occurring within the intake manifold above the throttle valve are imparted at the flexible diaphragm 80. In this case, however, the only office 30 of the latter is to control the extent of the opening 62 and therefore the valve 56, 66 is single acting. When the throttle valve 16 is closed, a vacuum is established within the intake manifold, causing that same vacuum to be imparted through the tube 88 and the duct 94 to the interior of the flexible diaphragm 80. This, of course, causes the diaphragm to collapse, tending to close off or restrict the amount of anti-detonating 35 fluid flowing through the passageway 62. Reversely, when the throttle valve 16 is wide open, the vacuum is entirely destroyed and the spring 82 moves the diaphragm 80 into its extended position, thereby allowing the maximum amount of 40 anti-detonating fluid to enter through the valve opening 62. It will be observed that in this device there is no ball valve such as is used in connection with the diaphragm 32 of the temperature control unit 26. Without the employment of any 45 such valve, fluctuations in pressure are quickly transmitted to the interior of the fluid control unit, causing it to respond immediately and with the result that the amount of anti-detonating fluid supplied will be immediately responsive to, and in exact proportion with, fluctuations in pressure 50 within the manifold. This, it has been found, is more desirable in some installations than having both the fluid control unit and the temperature control unit operated by the same 55 diaphragm.

In conclusion, it will be seen that applicants have provided a temperature control unit which 60 retards or delays the introduction of cold air to the manifold upon the imposition of load or speed and have combined therewith means for introducing anti-detonation fluid instantly upon the imposition of such load or speed. It will be appreciated that the illustrated embodiment of the 65 invention is merely suggestive and that modifications of the design and arrangement of the apparatus may be made from time to time without departing from the scope of the invention as set forth in the appended claims.

Having thus described the invention, what we

claim as new and desire to secure by Letters Patent of the United States is:

1. That improvement in methods of carburetion for internal combustion engines which comprises controlling the temperature of the combustible mixture in response to pressure changes occurring within the intake manifold and independently controlling the injection of anti-detonation fluid in response to such changes in pressure, the temperature control and the fluid injection bearing a predetermined timed relation. 10

2. That improvement in methods of carburetion for internal combustion engines which comprises introducing into a fuel stream anti-detonating fluid and combustion supporting fluid, the 15 introduction of both fluids being dependent upon variations in pressure occurring within the intake manifold, changes in the amount of one of said fluids introduced being arranged to lag changes in the amount of said other fluid being 20 introduced.

3. That improvement in methods of carburetion for internal combustion engines which comprises varying the temperature of the fuel stream slowly in accordance with variations in 25 pressure occurring within the intake manifold and varying the injection of an anti-detonating fluid more quickly in accordance with said variations in pressure.

4. That improvement in methods of carburetion 30 for internal combustion engines which comprises controlling the temperature of air admitted to a fuel stream in accordance with variations in the pressure of the fuel being fed, delaying the change in temperature of the air 35 admitted upon a sudden increase in the amount of fuel being fed and adding to the fuel stream without delay material for reducing detonation of said fuel.

5. That improvement in methods of carburetion 40 for internal combustion engines which comprises controlling the temperature of air admitted to a fuel stream in accordance with variations in the pressure of the mixture, delaying the change in temperature of the air admitted 45 upon a sudden increase in the pressure of the mixture and adding to the mixture, material for reducing detonation of said fuel, said anti-detonating material being supplied without delay in proportion to variations in pressure occurring 50 within the mixture.

6. A carbureting system for internal combustion engines having, in combination, means for controlling the temperature of air fed into a fuel stream and independently operable means 55 for controlling the amount of an anti-detonating fluid supplied to said fuel stream, the operating characteristics of said temperature controlling means and said fluid supplying means bearing a predetermined timed relation. 60

7. A carbureting system for internal combustion engines having, in combination, means for governing the temperature of air supplied to the intake manifold of the engine, said means being responsive to fluctuations in pressure occurring 65 within the intake manifold, and means for independently governing the admission of an anti-detonating fluid to the intake manifold of the engine, said latter named means being controlled likewise by fluctuations in pressure occurring 70 within the intake manifold, the operating characteristics of said temperature governing means and said anti-detonating fluid governing means bearing a predetermined timed relation.

8. A carbureting apparatus for internal com- 75

- bustion engines having, in combination, a unit for controlling the temperature of air admitted to the intake manifold of the engine and a device for independently controlling the admission of an anti-detonating fluid into said intake manifold, the operating characteristics of the temperature controlling unit and said fluid controlling device bearing a predetermined timed relation, said control device comprising a flexible diaphragm, means connecting the interior of said flexible diaphragm with the intake manifold of the engine, a valve carried by said flexible diaphragm, and a valve opening, the size of which is adapted to be regulated by the position of said valve.
15. 9. In a carbureting system for internal combustion engines, the combination of a hot air intake, a cold air intake, a valve intermediate said intakes for proportioning said hot and cold air into a fuel stream, means for controlling said valve according to pressures within a manifold, a water intake, a valve intermediate said water intake and said manifold and independently operable means for controlling said valve according to pressure changes in the manifold, the operating characteristics of said air-proportioning valve and said water-intake valve bearing a predetermined timed relation.
10. In a carbureting system for internal combustion engines, the combination of a hot air intake, a cold air intake, a valve intermediate said intakes whereby the amount of hot and cold air may be varied to obtain a given temperature in a fuel stream, operating means for the air valve comprising a stem on said valve, a bellows on said stem, a conduit connecting the interior of said bellows with the engine manifold whereby changes in pressure in said manifold will expand or contract said bellows and thereby control admission of hot and cold air into the fuel stream, a water intake, a valve intermediate said water intake and said manifold, operating means for the water valve comprising a stem on said valve and a bellows thereon, and a conduit connecting the interior of said bellows and said manifold whereby pressure changes in the manifold expand or contract said bellows to control the admission of fluid into said manifold, the operating characteristics of the operating means for the air valve and water valve bearing a predetermined, timed relation.
15. 11. In a carbureting system for internal combustion engines, the combination of a valve intermediate hot and cold air intakes and feeding a fuel stream, a stem on said valve and bellows on said stem, said bellows being rigidly fastened to some portion of the engine, a conduit connecting the interior of said bellows with a manifold, and a valve in said conduit having a ball bearing therein slidably operative to prevent the rapid expansion of said bellows upon increases of pressure in the manifold whereby cold air is slowly injected into the fuel stream, a water intake, a valve intermediate said water intake and said manifold, a stem on said valve and bellows on said stem rigidly fixed to the engine, a conduit connecting the interior of said bellows with said manifold whereby said bellows reacts instantly to pressure changes in the manifold.
16. 12. In a carbureting system for internal combustion engines, the combination of a temperature controlling unit which increases the temperature of the fuel stream with variations in the pressure within the engine intake manifold, and an independently operable anti-detonation control unit comprising an anti-detonating fluid intake, a valve in said intake, a stem on said valve and bellows on said stem rigidly fastened to the engine, and a conduit connecting the interior of said bellows with said manifold, whereby increases in pressure in the manifold open said valve, permitting an ejection of anti-detonating fluid into the manifold, the operating characteristics for said temperature controlling unit and said anti-detonating fluid control unit bearing a predetermined timed relation.
17. That improvement in methods of carburetion for internal combustion engines which comprises controlling the temperature of the fuel in response to pressure changes occurring within the intake manifold and controlling the injection of anti-detonation fluid in response to such changes in pressure, the control of the injection of the anti-detonation fluid being more quickly responsive to said pressure changes than the control of the temperature of the fuel.
18. A carbureting system for internal combustion engines having, in combination, means for controlling the temperature of air fed into a fuel stream and independent means for controlling the amount of anti-detonating fluid supplied to said fuel stream, the functioning of the temperature controlling means lagging behind the functioning of the anti-detonating fluid controlling means.
19. In a carbureting system for an internal combustion engine having an intake, means for governing the temperature of the combustible mixture supplied to the intake, said means being controlled by variations in the pressure within the intake, and independently operable means for controlling the introduction of anti-detonating fluid into said intake, said last-named means also being controlled by variations in the pressure within the intake and operating in timed relation to the operation of said first-named means.
20. In a carbureting system for an internal combustion engine having an intake, means for governing the temperature of the combustible mixture supplied to the intake, said means being controlled by variations in the operating conditions within the intake, and independently operable means for controlling the introduction of anti-detonating fluid into said intake, said last-named means also being controlled by variations in the operating conditions within the intake and functioning in predetermined timed operating relation to the operation of said first-named means.
21. In a carbureting system for an internal combustion engine having an intake, means for governing the temperature of the combustible mixture supplied to the intake, said means being controlled by variations in the operating conditions within the intake, and independently operable means for controlling the introduction of anti-detonating fluid into said intake, said last-named means also being controlled by variations in the operating conditions within the intake and having operating characteristics different from but bearing a predetermined timed relation to those of said first means, whereby operation of both means may be simultaneously initiated and the temperature and anti-detonation fluid control will bear a predetermined relation.
